UNITED STATES PATENT OFFICE

2,435,452

COLOR INKER FOR CYLINDER PRESSES

Albert W. Linn and Albert C. Forbes,
Memphis, Tenn.

Application May 5, 1945, Serial No. 592,150

3 Claims. (Cl. 101—350)

1

This invention relates to auxiliary devices for inking the type plates of printing presses of the cylinder type, such as are used in printing newspapers, and has especial relation to devices which may be attached to and removed from standard cylinder presses, where it is desired to print a page or portion of a page of the paper in ink other than that being used in the body of the paper, as when portions of a page are to be printed in red or other color and over-printed in the usual blank ink.

In modern newspaper presses, the paper is fed continually between the type plates of page width, and impression cylinders which hold the paper against the type and print one side of the page, the paper then continuing an additional pair of cylinders which print the opposite side of the page, and where over-printing is to be done, to a third pair of cylinders where such over-printing is done, the printing sequence varying as occasion may demand.

These presses each have several banks of rolls, each bank including a type cylinder roll and numerous rolls which feed into the type cylinders. The rolls are of length to carry a number, usually four, type plates of page width, each plate being precast in semi-cylindrical form and secured on the roll, and as many, usually up to four, being used as it is desired to print pages of the paper on that pass.

All the type plates on one roll are inked at the same time by the related group of ink feeding rolls which are supplied from an underlying trough or fountain and which effect proper distribution of the ink and obviously must use ink of a single color. The direction of rotation of these rolls is governed by the direction of rotation of the type plates, which in turn is dependent on whether the under or upper side of the sheet is being printed.

From time to time it occurs that it is desirable to print a single page in a different color, or to print color touches on a page and over-print in standard color ink. This may be done by use of a single type plate for the desired page and the regular ink distributing system, but requires the cleaning of the distributing troughs or fountains, both before and after use, an almost prohibitive task, and involves the use of and loss of such excessive quantities of both regular and special inks that it is scarcely ever warranted. Additionally, should it be desired to print the pages of differing color it is impossible.

The present invention contemplates an auxiliary ink feeding mechanism usable in connection with the regular ink distributing rollers, which auxiliary mechanism may be temporarily substituted for the regular feeding mechanism, which mechanism may be attached to and detached from the press, and positioned to deliver

ink to any desired section of the ink distributing rolls and thereby in usual manner to the type plate inked by such action of the rolls.

The objects of the present invention are:

5 To provide an auxiliary inking mechanism which is attachable to frame portions of a cylinder press and driven by ink distributing rolls thereof to feed ink to a local section of such rolls;

10 To provide an auxiliary ink feeding mechanism, including a supporting frame which is conformable for attachment to a particular press with which it is to be used, which mechanism is adjustable with respect to such frame to establish driving contact with an ink distributing roll of the press;

15 To provide an auxiliary ink feeding mechanism engageable with an ink distributing roll of a cylindrical press and driven thereby, having driving means for the ink pick-up portion of such mechanism effective to reverse the direction of rotation of such pick-up portion with relation to the other portions thereof;

20 To provide an auxiliary inking mechanism including a pick-up roll and means for regulating the amount of ink delivered by such roll;

25 To provide an auxiliary ink feeder which may be substituted for a regular ink feeder of a cylinder press to locally feed to the related ink distributing rolls ink of a desired color.

30 The means by which the foregoing and other objects are accomplished, and the manner of their accomplishment, will readily be understood from the following specification upon reference to the accompanying drawings, in which:

35 Fig. 1 is a transverse sectional elevation through the feeder and supporting frame therefor, with the driving roller of the feeder in driven contact with a roll of a cylinder printing press.

Fig. 2 is an end elevation of the feeder.

40 Fig. 3 is a fragmentary sectional elevation of the same end of the feeder with the driving mechanism cut away to show the adjusting mechanism for roller bearings thereof.

Fig. 4 is a plan view; and

45 Fig. 5 a fragmentary sectional front elevation showing the driving end of the mechanism.

Referring now to the drawings in which the various parts are indicated by numerals:

50 11 and 13 are stationary rods or members which form a usual part of the frame of a cylinder printing press, and 15 a fragmentary portion of one of the ink distributing rolls of such a press.

55 In the auxiliary feeder herein described, a supporting frame is provided which has end members 17, which members are notched for engagement with the press member 13. 19 are vertically disposed members rigidly secured to the members 17, and 21 additional vertical members slidably adjustable with respect to the members 19 and clamped when adjusted as by the bolts 22. The

members 21 are notched at their upper ends for engagement with the other press member 11 for attachment of the device to the press and are clamped thereto as by the set screw 23.

Integrally secured to the end members 17 and longitudinally extending therebetween are base members 24 which are adapted to support an ink trough 25 in which the ink 26 is carried. This trough is substantially of the length of a type cylinder of the press, has a front wall 25A, bottom 25B, back wall 25C, roughly of the same height as the front wall, and end walls 25D, which have upwardly extending portions 25E, 25F spaced apart to form guides for journal blocks 27 and 29. The upper of these blocks journal the shaft 31 of a driving and ink transferring roll 33 which has a resilient cover 33A, as of rubber, adapted for driving contact with the press roll 15 and for transfer of ink thereto.

The blocks 29 journal the shaft 35 of an intermediate roll 37, which contacts and is driven by the resilient surface 33A of the roll 33 and is adapted to transfer ink thereto.

Disposed below the roll 37 is an ink pick-up roll 39 which is mounted on a shaft 41 journalled in the end walls 25D of the ink trough, this roll being spaced in such adjacency to, but not in contact with the roll 37, that it will deliver ink picked up from the trough to the roll 37, but may be driven in the same peripheral direction or the opposite direction with reference to the roll 37. Preferably the rolls 37 and 39 are of metal accurately turned and polished in order that the spacing therebetween may be uniform and not vary.

The blocks 29 journaling the roller 37 are supported by screws 43 through which they may be adjusted toward or away from the roll 39 to secure the desired clearance between the surfaces of the two rolls, and after adjustment are clamped by the screws 45. The blocks 27 journaling the roller 33 may be adjusted relatively to the blocks 29 to secure the proper contact between the rollers 37 and 33, and after such adjustment may be clamped to the guide blocks 25E and 25F by the screws 47.

Mounted on the end walls 25D of the trough is a bar 49 to the underside of which is secured a thin flexible strip or stripper 51 which is deflected by thumb screws 53 into adjacency to or contact with the roller 39 to strip off surplus ink carried upward from the trough by the roller, the screws preferably being uniform distances apart along the length of the bar.

The ink pick-up rolls 39 must turn in relation to this stripper so that the surplus ink stripped off will drain back into the trough and can, therefore, only be driven in the direction of the arrow D irrespective of the direction in which the other rollers turn.

The shaft 41 of the roller 39 extends beyond one of the end walls 25D and has secured thereon a worm wheel 55, with which meshes a worm 57. The worm 57 is secured on a vertically disposed shaft 59, which at its upper and lower ends is journalled in blocks 61, 63 respectively, which are carried by the adjacent end wall and guide members 25D, 25E and 25F of the ink trough.

Secured on the upper end of the shaft 59 are beveled pinions 65 and 67 which are adapted to mesh with a bevel pinion 69 on the shaft 31 which carries the upper roller 33, the gears 65 and 67 being so spaced apart that only one or the other may so mesh. Spaced equally respectively above and below the brackets 61 and 63 are additional

brackets 71 and 73, the spacings of these brackets, as the bracket 71 from the bracket 61, being equal to the amount of shift necessary to move the pinion 67 out of mesh with and the pinion 65 into mesh with, the pinion 69. The shaft 59 projects through the bracket 61 into engagement with the bracket 71 when the pinion 65 is out of mesh with the pinion 69, the opposite end of the shaft being flush with the underside of the bracket 63 and the pinions 67 and 69 in mesh.

75 is a removable block, here designated a reverse plate, which is interposed between the brackets 63 and 73 and in engagement with the lower end of the shaft 59 to hold the pinions 67 and 69 in this engagement. This plate is removed and used between the upper brackets 61 and 71 to engage the upper of the shaft 59 and hold the pinion 65 in mesh with the pinion 69 to reverse the direction of rotation of the worm 57 and through it the worm gear 55 and drive the roller 39 oppositely with respect to the rollers 33 and 37.

Secured to the opposite ends 17 of the support frame is an anchor bar 77, and secured to the back 25C of the ink trough is a complementary anchor clamp 79 which may be engaged with the clamp bar to secure the ink trough against displacement relatively to the supporting frame and the press rolls. Adjacent its front, brackets 81 are secured to the opposite ends 25D of the trough, these brackets having horizontally extending legs 81A through which set screws 83 are disposed, the lower ends of these screws seating on the forward one of the base members 24 of the frame and being adapted to raise the front edge of the trough and correspondingly tip the upper roller 33 into driving contact with the roll 15 of the press and provide adjustment through which the contact pressures of the roller and roll may be adjusted.

To prepare the inker for use, the roller 37 is adjusted relatively to the roller 39 to establish a clearance of about two thicknesses of news print paper therebetween and the roller 33 into rolling and driving contact with the roller 37, relations being later further adjusted as results obtained under use warrant. The stripper is deflected by the screws 53 into adjacency with, but not in contact with, the roll 39.

50 In using the inker, the ink pick-up roll of a bank of type cylinders and ink feeding rolls, with which color is to be used, is ordinarily removed. The supporting frame for the auxiliary inker is mounted on the frame members 11 and 13 of the press in substantial alinement, longitudinally of the press rolls, with the type cylinder which is to be color inked and is securely clamped in place.

The ink trough 25 and roller assembly is placed on the base members 24 of the frame and if not already projecting the set screws 83 are run down to project slightly through the bracket legs and tip the roller 33 slightly backward. The assembly is shifted longitudinally into alinement with the type cylinder to be inked and the roller 33 into engagement with the roll 15, with the anchor clamp 79 embracing the anchor bar 77. When positioned the clamp 79 is tightened on and anchored to the bar 77 and the screws 83 tightened or loosened to adjust the roller and roll contact.

Depending on the direction in which the roll 15 turns, the reverse plate 75 is inserted beneath or above the end of the shaft 59 and the proper pinions 67 and 69, or 65 and 69 are engaged so that the roller 39 will be caused to turn in the direction of the arrow D. The ink trough is filled

to desired level with ink 26 of the color to be used, and the inker is ready for a trial run.

As the presses start, the roller 39 picks up ink and carries it past the stripper 51 to the roller 37. The pressman adjusts the screws 53 to restrict or increase the amount of ink passing the stripper and effect a fairly uniform film of ink on the roller 39, and may also adjust the pressure of the roller 33 against the roll 15, or the roller 37 and the spacing of the rollers 37 and 39. The roller 37 transfers the ink to the roller 33, and thence to the roll 15 and that roll transfers it to the other distributing rolls and the type cylinder which is to be inked.

As proofs are delivered from the press they are examined by the pressman and such adjustment of the stripper with respect to the roller 39 is made as is necessary to even up and increase or decrease the flow of ink as the proofs indicate lack or surplus, such observation and adjustment usually being continued from time to time during the printing of the paper.

One of the functions of the distributing rolls of the press is to effect longitudinal distribution of the ink along the rolls as well as around them, such distribution is, however, of minor amount and extends little beyond the type margins of the page being printed, where a page wide inker is used.

If desired, two color inkers using different colored ink may be used at one time for a four page press.

It will be understood that the term "rollers" has been used in the description of the auxiliary inker solely for the purposes of distinguishing from more or less similar rolls of the press.

We claim:

1. An auxiliary device for inking type plates of a cylinder printing press having ink distributing rolls; which device includes an ink holder or trough, rollers having shafts carried and journaled in bearings carried by said trough, including an ink pick-up roller depending into said trough, an intermediate roller in ink transfer adjacency above said pick-up roller, but not in contact therewith, and an ink transfer roller in driving contact with and above said intermediate roller; means for supporting said trough from and anchoring same to said press, with said transfer roller in driven and ink transfer contact with a distributing roll of said press, means for regulating the amount of ink delivered by said pick-up roller to said intermediate roller, and means for driving and reversing the direction of rotation of said pick-up roller relatively to said transfer roller, comprising a worm wheel mounted on the shaft of said pick-up roller, a worm meshing with said wheel, bearings carried by said trough, a shaft carrying said worm journaled in said bearings and longitudinally shiftable with relation to said bearings, said shaft extending across the end of the shaft of said transfer roller, a bevel driving gear carried by said transfer roller shaft, a pair of complementary bevel gears mounted on said shaft in spaced relation and position for respective engagement with said driving gear by opposite longitudinal shift of said shaft, means translatable at option to engage and hold said shaft and gears carried thereby in either shifted position to effect said reversal.

2. An auxiliary device for inking type plates of a cylinder printing press having ink distrib-

uting rolls; which device includes an ink holder or trough, rollers having shafts carried and journaled by said trough, including an ink pick-up roller depending into said trough, an intermediate roller in ink transfer adjacency to said pick-up roller, but not in contact therewith, and an ink transfer roller in driving contact with said intermediate roller; means for supporting said trough from and anchoring same to said press, with said transfer roller in driven and ink transfer contact with a distributing roll of said press, means for regulating the amount of ink delivered by said pick-up roller to said intermediate roller, and means for driving and reversing the direction of rotation of said pick-up roller relatively to said transfer roller, comprising a worm wheel mounted on the shaft of said pick-up roller, a worm meshing with said wheel, bearings carried by said trough, a shaft carrying said worm journaled in said bearings and longitudinally shiftable with relation thereto, said shaft extending transversely to and beyond the shaft of said transfer roller, a bevel driving gear carried by said transfer roller shaft, a pair of complementary bevel gears mounted on said shaft in spaced relation and position for respective engagement with said driving gear by opposite longitudinal shift of said shaft, bracket members carried by said trough respectively overlying the opposite ends of said shaft, and a block optionally translatable into engagement between either end of said shaft and the related said bracket member to maintain said shift and gear engagement.

3. An auxiliary device for inking a type plate of a cylinder printing press, having ink distributing rolls; which device includes an adjustable supporting frame adapted to be positioned along transverse members of said press, means for detachably anchoring said frame to said members; and ink feeding means comprising a unitary assembly, adjustably supported by said frame and removable therefrom; said assembly including an ink trough having upwardly extending end walls, a pick-up roller depending within said trough, an intermediate roller above and adjacent to but not contacting said pick-up roller, and a transfer roller above and in driving contact with said intermediate roller, said end walls carrying bearings journaled said rollers; means for anchoring said assembly to said frame, and means for tilting said assembly with respect to said frame for shifting said transfer roller into driven contact with an ink distributing roll of said press; means for regulating ink delivery from said pick-up roller to said intermediate roller, means for driving said pick-up roller from said transfer roller, and means for reversing the relative direction of said drive.
